ALBEN E. LUNDELL, OF NEW YORK, N. Y., ASSIGNOR TO WESTERN ELECTRIC COMPANY, INCORPORATED, OF NEW YORK, N. Y., A CORPORATION OF NEW YORK.

IMPULSE-CONTROL SYSTEM.

1,242,009.

Specification of Letters Patent.

Patented Oct. 2, 1917.

Application filed May 25, 1916. Serial No. 99,749.

To all whom it may concern:

Be it known that I, ALBEN E. LUNDELL, a citizen of the United States, residing at New York, in the county of Bronx and State 5 of New York, have invented certain new and useful Improvements in Impulse-Control Systems, of which the following is a full, clear, concise, and exact description.

This invention relates to telephone exchanges 10 and more particularly to impulse control systems for selector switches in automatic telephone exchanges.

The lines and trunks in automatic telephone systems being arranged in groups, the 15 automatic selector switches are equipped with means for primarily selecting a desired group, and then for selecting, during a secondary movement, an idle line in the selector group. The primary motion of the switch 20 is controlled by an impulse mechanism, and in order to insure the change-over from the primary operation of the switch to the secondary operation, a timing device, such as a slow-acting relay, is provided in association 25 with the switch. This relay does not respond to the operations of the primary impulse receiving means associated with the selector, but becomes actuated upon the cessation 30 of the primary impulses, and causes the switching out of the primary and the switching in of the secondary operating means.

It is the object of this invention to provide an impulse controlling system in which 35 the necessity of providing such a timing device for controlling the change-over from the primary to the secondary operation of the selector switch, is obviated.

With this object in view, this invention 40 provides a system in which the electromagnetic means controlling the primary operation of the selector switch is conductively associated with the impulse circuit, and the electromagnetic means controlling the secondary 45 operation of the selector switch is inductively united with but conductively separated from this circuit.

Figure 1 is a diagrammatic view of a telephone exchange system embodying the present invention, only so much being shown of the circuits and apparatus as is necessary for a clear understanding of the present invention.

Fig. 2 is a diagram, indicating the cur-

rent changes produced in the impulse sending circuit.

The calling device, by means of which an impulse receiving relay 10 and a change-over relay 12 may be controlled, is represented at 11. The calling device comprises 60 a dial 13, provided with a plurality of finger-holds 14, by means of which the dial may be moved toward a stationary stop 15. Upon the release of the dial, a motor spring, (not shown) wound up during the forward 65 movement of the same, causes the return of the dial, and during this return movement, a pawl 16 pivoted on an arm 17 of dial 13 engages the ratchets of a wheel 18 and causes it to rotate with the dial. The ratchet 70 wheel 18, through the agency of a gear wheel 19, causes an arm 20 to travel over a commutator 21 in the direction indicated by the arrow, the ratio between the movement of the arm 20 and the dial 13 being such 75 that for each finger-hold by which the dial 13 has been displaced, the arm 20 will perform one complete revolution. The dial is so adjusted that an insulated lug 24 on member 20 causes the closure of a contact 25 prior 80 to the engagement of a segment 26 of commutator 21, by arm 20.

Upon the removal of the receiver from the switchhook, at substation 27, a circuit is closed from grounded battery through the 85 winding of relay 10, the primary winding of an induction coil 28, a side-switch wiper 29, conductor 30, the substation circuit, conductor 31, contact 25, conductor 32, and a side-switch wiper 33 to ground. Due to the 90 infinitely high resistance of this circuit prior to its closure, no current is flowing in the same. Upon the sudden closure of the circuit at the contacts of the hook switch, the resistance of the circuit will be suddenly 95 reduced, and the surge of current thus produced in the circuit will cause the induction of sufficient current through the secondary winding of induction coil 28 to cause the energization of relay 12. The resistance of the impulse circuit being maintained at the same point, the amount of current flowing in this circuit will remain the same, and relay 12 becomes deenergized. Upon its 100 energization, relay 12 closes an energizing circuit for the side-switch magnet 34, which, upon the opening of its circuit, causes the side-switch wipers to move into position 2.

These changes of current in the circuit are indicated in Fig. 2, to the left hand of a dotted line 35.

The calling subscriber now inserts his finger into the finger-hold 14, representing the desired number of digits, and moves dial 13 until his finger reaches the stop 15. When the lug 24 disengages spring 36, contact 25 is opened. The above traced circuit, however, remains closed through conductor 37, segment 26 of commutator 21, arm 20 and conductor 38. Upon the release of contact spring 36, contacts 40 engage spring 41, causing thus, the short-circuiting 15 of the subscriber's receiver for preventing the occurrence of objectionable noises.

Supposing that the third finger-hold 14 was selected, during the return movement of dial 13 and wheel 18, arm 20 will complete three revolutions. While traveling over segments 45 of commutator 21, arm 20 includes increasing portions of a resistance 46 into the impulse sending circuit, causing thus, the gradual reduction of current in 25 this circuit until a segment 47 is reached, when the circuit is opened, and thus the current flowing therein is zero. Arm 20 then continuing its rotation, includes into the circuit decreasing portions of resistance 30 46 through segments 48, causing the gradual increase of current in the impulse sending circuit. The wavelike changes of current, which are represented in Fig. 2 between dotted lines 35 and 49, are gradual, 35 and therefore the current induced into the circuit of relay 12 will not be of sufficient strength to energize this relay.

When the current reached a sufficiently low value, relay 10 became deenergized and 40 opened the circuit of a primary magnet 50, which caused the stepping of the wipers of a selector 51 in a primary direction. This operation of sender 11, relay 10 and magnet 50 will be repeated as many times as 45 predetermined by the number of digits selected and when the current in the impulse sending circuit reaches the zero point for the third time, arm 20 being in engagement with segment 47, arm 17 of dial 13 engages 50 spring 36 and causes the closure at contact point 25 of the originally traced circuit of relay 10, producing a sudden change of resistance, which will result in the induction of sufficient current in the circuit of relay 55 12 for operating the same. Arm 20 returns to its normal position without causing any further effect on the impulse sending circuit. Upon the deenergization of relay 12, which shortly follows its energization, side- 60 switch magnet 34 again becomes deenergized, and by moving the side-switch wipers into position 3, causes the connection of an interrupter 70 in circuit with a secondary magnet 71, which controls a secondary or 65 trunk-hunting motion of selector switch 51.

While a test wiper 72 is traveling over grounded, *i. e.* busy, terminals, side-switch magnet 34 will be maintained energized, and when an idle terminal is reached, this magnet becomes deenergized and moves the side-switch wipers into position 4, disconnecting, thus, the secondary magnet and connecting conductors 30 and 32 to the wipers of selector 51. 70

Upon the termination of the conversation, 75 an impulse is sent through wiper 72, conductor 75 and the winding of a release magnet 76 for operating the same. The release magnet causes the restoration of selector 51 and the associated side switch. 77 is an off-normal contact of selector 51. During the sending out of the impulse, the selector 51 is not released, as the circuit closed through the armature and back contact of relay 10 and the off-normal contact 77 is not maintained 80 closed for a sufficient length of time for energizing the somewhat sluggish magnet 76. Should, however, the calling subscriber desire to abandon the connection, by hanging up the receiver he will cause the 85 continued deenergization of relay 10, whereupon the release magnet will become energized. 90

While the invention has been described as applied to a telephone system in which 95 the selector switches are controlled under the directive control of an impulse-sending device, it will be obvious to those skilled in the art that it is applicable to impulse-sending systems of widely varying character, such as retractive-impulse systems, in which the selector rather than the impulse device causes the sending out of impulses. 100 It will be further apparent that instead of an induction coil, other well-known apparatus, such as a condenser, may be employed for inductively connecting but conductively separating the relay 12 and the impulse-sending circuit. 105

What is claimed is:

1. In a telephone exchange system, an incoming line and groups of outgoing lines, a selector switch, an impulse sender associated with said incoming line, means controlled by said impulse sender for producing wave-like current fluctuations in said incoming line, means responsive to said current fluctuations for causing said selector to select a desired group of outgoing lines, means controlled by said impulse sender for producing a sudden change of resistance in said incoming line, and means operative thereupon for causing said selector to hunt for an idle line in said selected group of outgoing lines. 115

2. In a telephone exchange system, an incoming line and groups of outgoing lines, a selector switch, an electromagnetic means for controlling said switch to select a group of outgoing lines, another electromagnetic 120 125 130

means for controlling said switch to seize a line in the selected group, switching means for controlling the successive operation of said electromagnetic means, a relay inductively associated with said incoming line, means operable through said incoming line for actuating said relay, and means operated thereupon for actuating said switching means.

10 3. In a telephone exchange system, an incoming line and groups of outgoing lines, a selector switch, an electromagnetic means conductively associated with said incoming line and operable therethrough for controlling said selector to seize a group of outgoing lines, and another electromagnetic means inductively associated with said incoming line and operable therethrough for causing said selector to hunt for an idle line 20 in the selected group of outgoing lines.

4. In a telephone exchange system, a plurality of subscribers' stations, a selector switch arranged to establish a connection from one of said stations toward another 25 station in accordance with the group and line designation of said latter station, a circuit extending from the calling station to said selector switch, a relay included in said circuit for controlling the group selecting 30 operation of said selector, and a relay inductively connected to said circuit and operable therethrough for controlling the line selecting operation of said selector.

5. In a telephone exchange system, a calling 35 and a called station, a selector switch arranged to perform a primary and a secondary operation to interconnect said stations, a circuit between said calling station

and said selector, electromagnetic means included in said circuit for causing the primary operation of said selector, and another electromagnetic means inductively connected to said circuit and operable therethrough for controlling the secondary operation of 40 said selector.

6. In a telephone exchange system, two telephone stations, a selector switch for interconnecting said stations, electromagnetic means for controlling a primary operation, and another electromagnetic means for controlling a secondary operation of said selector switch, a circuit extending from the calling station to said selector, means for producing wave-like current changes and means for producing sudden changes of resistance in said circuit, means for operating said first mentioned electromagnetic means in accordance with the wave-like current changes produced in said circuit, and means for operating said second mentioned electromagnetic means in accordance with the sudden changes of resistance produced in said circuit.

7. In combination, a selectively operable switch adapted to perform a primary and a secondary motion, a controlling circuit for said switch, an electromagnetic means at said switch for controlling said primary motion conductively connected to said circuit, and another electromagnetic means at 25 said switch for controlling said secondary motion inductively connected to said circuit.

In witness whereof, I hereunto subscribe my name this 24th day of May A. D., 1916.

ALBEN E. LUNDELL.
